PLACE MAT OR SIMILAR ARTICLE

Kenneth C. Hamilton, Milwaukee, Wis., assignor to Milwaukee Lace Paper Company, Milwaukee,
Wis., a corporation of Wisconsin

Application July 13, 1953, Serial No. 25,901

Term of patent 14 years

(Cl. D59—2)

To all whom it may concern:

Be it known that I, Kenneth C. Hamilton, a citizen of the United States, residing at Milwaukee, in the county of Milwaukee and State of Wisconsin, have invented a new, original, and ornamental Design for a Place Mat or Similar Article, of which the following is a specification, reference being had to the accompanying drawing forming a part thereof.

The figure of the drawing is a face view of a half-section of a place mat embodying my new design, which design is repeated in the other half-section of the place mat.

The design is an open work shown in the drawing on a dark background to better bring out the details thereof.

I claim:

The ornamental design for a place mat or similar article, substantially as shown and described.

KENNETH C. HAMILTON.
